GOOGLES STRUCTURE

William R. Christensen, Newton Highlands, and
Chester E. Cross, East Sandwich, Mass.

Application June 8, 1949, Serial No. 97,861

12 Claims. (Cl. 2-14)

(Granted under the act of March 3, 1883, as
amended April 30, 1928; 370 O. G. 757)

1

The invention described herein, if patented, may be manufactured and used by or for the Government for governmental purposes without the payment to us of any royalty thereon.

This invention relates to anti-fogging and anti-frosting goggles, and more particularly to improved ventilating structure to prevent condensation of moisture on the goggles lenses.

Broadly, in principle, it has been found that ventilation of the eyecup cavities of goggles when the latter are to be used under climatic conditions likely to produce fogging or frosting greatly reduces such fogging or frosting. However, the means for producing a flow of ventilating air in the eyecups must be designed to produce currents coinciding with the normal convection currents of the goggles cavities in so far as possible, to provide a ready and rapid removal of moist air, and thus prevent condensation of moisture upon the goggles lens.

Accordingly, it is an object of this invention to provide an improved heat conducting and ventilating structure for a goggles to prevent fogging and frosting of the goggles lenses.

It is another object of this invention to provide an improved means to control the flow of air through the air circulating structure of a goggles.

It is a further object of this invention to provide an improved anti-fogging and anti-frosting goggles structure wherein there is continuous and rapid removal of excessive humidity from the goggles cavities.

It is a further object of this invention to provide an improved goggles structure wherein guided and relatively controlled air currents coincide with normal convection currents within the goggles cavities to continuously and rapidly remove excessive moisture from the cavities.

Further objects, advantages, adaptations and uses of this improvement in goggles structure will be readily apparent from the following description and the accompanying drawings, wherein:

Figure 1 is a front elevational view of a goggles structure embodying the invention;

Figure 2 is a bottom view of the goggles;

Figure 3 is a top view of the goggles, with the top ventilating means partially broken away;

Figure 4 is a cross-sectional view on line 4-4 of Figure 1;

Figure 5 is a partial perspective of the outlet of the ventilated goggles shown in Figures 1 and 3; and

Figures 6, 7, 8 and 9 are plan views of blank sheets from which the ventilator structures are made.

2

Referring to the drawings, the goggles comprises a frame 10 constructed of rubber or other like material of a flexible resilient nature, having a curved face-contacting side 11 and a lens-holding bead 12, separated by a circumferential web 13 of conventional arrangement. Bead 12 contains a groove 14, within which a conventional lens 15 of a cellulose acetate, or other suitable material, is inserted and held by conventional snap fasteners 16. The ventilating means comprising air outlet structure 17 and air inlet structure 18 is mounted respectively in the upper and lower edges of the frame 10. The latter is provided with conventional head straps 19, secured in ears or lugs 20 on the frame 10 by the strap end enlargements 19'. In addition, the nose bridging portion of goggles frame 10 may be provided with a flexible chamois or cloth material 21 for protection of the wearer's nose against excessive cold. This protector 21 is secured to the goggles framework 10 by adhering it to the nose bridging part of the face-contacting portion 11 with a suitable rubber adhesive.

As illustrated in Figs. 1, 2 and 4, the air inlet structure 18 comprises a blank 18' shown in Fig. 9, preferably of thin malleable copper, bent on the dotted lines 22 to form a plurality of angularly disposed accordion folds or fins 24 and opposite ends 24'. When this inlet structure is disposed in assembled relation in the frame 10 the fins 24 cooperate with the lens 15 to form passageways of progressively increasing width from the inlet to outlet ends thereof so as to distribute incoming air over substantially the entire interior surface of lens 15.

The air outlet structure 17, illustrated in Fig. 5, is likewise formed of flexible metallic sheet material, the outlet comprising three blanks 25, 26 and 27, as shown in Figs. 6, 7 and 8, bent on dotted lines 28 to provide accordion folds or ribs 29. In the assembled relationship of the parts these ribs cooperate to form parallel series of air outlet passageways 30 and 31. The formed blanks 25, 26 and 27 are secured together by end pieces 32 which may be formed from separate strips or which may be formed by extending either end of blank 25 or blank 27 to provide overlapping junctures that are joined by soldering, or by the use of other suitable adhesive, such as rubber, resin or the like.

There is provided along one longitudinal edge of blank 25 a plurality of uniformly spaced dovetail shaped extensions 33. These extensions 33 are bent on dotted lines 34 into a plane normal to the strip 25 so as to extend over the air outlet

passageways 30 and 31. The opposite ends 33' thereof overlap to form a heat-conductive shield over the outlet passageways 30 and 31 which is adjustable by bending these extensions toward or from the outlet passageways so that control over the air flowing out of the eye-cup cavities of the goggles is possible. On the blank 26 there is likewise provided a plurality of uniformly spaced dovetail shaped extensions 35 which overlap when the blank 26 is folded on lines 28 to provide the ribs 29 previously mentioned. The extensions 35 depend downwardly into the goggles cavities, as illustrated in Fig. 1, when the parts are in assembled relation so that the overlapping edges 35' serve primarily as air separating means or partition for maintaining most of the cold air entering through inlet structure 18 closely adjacent the inner side of lens 15 so that very little of it mixes with the warmer moist air adjacent the eyes.

In the apparatus as described, slots 36 are provided in web 15 on each side of the nose bridging portion of frame 10 for receiving air inlet structures 18. The inlet structures 18 are secured in the slots 36 by the use of a suitable adhesive, as rubber, cellulose acetate or other securing means, as by molding or bonding the same in the frame or the like, as desired.

The outlet structures 17 is likewise secured in an aperture of appropriate size in the web 12 along the upper side of the frame 10. Preferably the front and back walls 37 and 38, respectively, on the outlet structure are secured, respectively, to the back of bead 12 and to the front of face-piece 11 so that the shield for the outlet passageways 30 and 31 faces rearwardly, and reverse air currents within the goggles cavities are thus prevented.

It will be observed that the accordion folds connecting adjacent passageways in the inlet and outlet forming means lend flexibility to the same. Likewise the fact that the overlapping ends of the extensions in the shield and partition are not secured together does not diminish the flexibility of the inlet and outlet forming means and furthermore this shield and partition will be continuous irrespective of the direction the frame 10 is flexed.

This apparatus as described is designed to operate without fogging or frosting under conditions of low ambient temperatures. Although the flow of air through the goggles structure may be more or less controlled by the adjustable extensions 33, it is preferable that the goggles be generally utilized under low wind conditions to avoid undue chilling of the eyes, caused by incoming cold air.

Under actual test conditions, it was found that the goggles as above described remained free of fog and frost for at least an hour's time at temperatures of from +30° to -20° F. These tests were made under working conditions within climatic test chambers of a conventional character.

In the arrangement described, when the extensions 33 and 35 are formed of material of high thermal conductivity, heat will be dissipated from the upper area of the eyecup cavities thus reducing the absorption of moisture by the air in the eyecup cavity. Also in conjunction with extensions 35, the outlet controls 33 aid in providing a measured or regulated flow of air over the inner surface area of lens 15 which is distributed through the eyecup cavity about a wearer's eyes. That is, incoming air from the passageways provided by inlets 18 primarily is directed to flow

over the lenses and out through the controlled passageways 30 whereas a less direct flow is caused to be distributed into the cavities about the eyes of a wearer to absorb facial moisture and carry it off through controlled passageways 31.

Although the above outlet structures are formed of flexible copper or other thin metallic conductor material, it will be apparent that a rubber or plastic adaption of this model can be constructed for insertion into or molded with the goggles frame. Further, if desired, the extension 35 may be formed of transparent acetate, resin or like material, to increase vertical vision.

In accordance with the patent statutes, the foregoing is a description in detail of what is now considered to be the illustrative form of the invention, but it will be obvious that various changes may be made in the structural details without departing from the spirit of the invention, and it is intended that all such changes be included within the scope of the appended claims.

We claim:

1. In a ventilated goggles having a lens supported in a frame which has a flexible face contacting part cooperating with the lens to define a substantially sealed space around the eyes of a wearer of the goggles the combination comprising, flexible ventilating air inlet forming means defining a plurality of passages projecting generally upwardly through the lower edge of the frame into the confined space closely adjacent the inner side of the lens on each side of the bridge of said frame, flexible outlet forming means extending through the top edge of said frame on the inner side of the lens, a plurality of extensions depending into the space behind said lens closely adjacent thereto from the top edge of said frame to form a partition, and a plurality of extensions on the outside of said frame extending backwardly over the passages in said outlet forming means to form a shield over the same, said extensions in said partition and said extensions in said shield respectively partially overlapping and being free of attachment to each other so that flexibility of the partition and shield is not appreciably diminished and said partition and shield are each continuous when the frame is flexed.

2. In a goggles having a lens supported in a frame which has a flexible face contacting part cooperating with the lens to define substantially sealed eyecups when the goggles are worn, the combination comprising means for directing a flow of external air through the eyecups closely adjacent the inner surface of the lens supported in the frame including inlet forming means in the frame immediately adjacent the inner side of the said lens on each side of the bridge of said frame for directing air generally upwardly along the inner side of the said lens and shielded outlet forming means extending longitudinally of the top of said frame and including means forming a partition closely adjacent the inner side of the said lens, said inlet and outlet forming means each comprising one or more continuous strips of relatively flexible material formed to provide a plurality of open passages defined by accordion folds in the strips so that flexibility of said air directing means is not diminished appreciably.

3. A goggles as defined in claim 2 wherein the shield on said outlet forming means comprises extensions on the portions of said strip forming the front wall of said outlet passages bent backwardly over the latter, said extensions being con-

formed partially to overlap when folded back and being free of attachment to each other so that flexibility of said outlet forming means is not appreciably diminished by said shield and said extensions form a continuous shield over the outlet forming means irrespective of which direction the lens frame is flexed.

4. A goggles as defined in claim 2 wherein the partition on said outlet forming means comprises a plurality of extensions depending into the space behind the said lens closely adjacent the inner side thereof, the depending ends of said extensions partially overlapping and being free of attachment to each other so that flexibility of the outlet forming means is not appreciably diminished thereby and said extensions form a continuous partition across the front of the goggles irrespective of the direction in which the frame is flexed.

5. A goggles as defined in claim 2 wherein the inlet and outlet forming means is formed from a material of high thermal conductivity.

6. In a ventilated goggles having a lens supported in a frame which has a flexible face contacting part cooperating with the lens to define a substantially sealed space around the eyes of a wearer of the goggles the combination comprising, flexible ventilating air inlet forming means projecting through the bottom edge of said frame closely adjacent the inner side of said lens, flexible outlet forming means extending through the top edge of said frame closely adjacent the inner side of said lens and including wall structure forming a plurality of flexibly interconnected passages arranged in side-by-side relation in two or more parallel rows extending longitudinally of the frame, means forming a shield on the outside of said frame extending over said outlet passages, and means forming a partition between parallel rows of outlet passages depending into the space in said goggles in close proximity to the inner side of said lens so that one row of passages forms an outlet for ventilating air immediately adjacent the inner side of said lens and the other forms an outlet for air behind said partition contacting the face of the wearer.

7. In a ventilated goggles having a lens supported in a frame which has a flexible face contacting part cooperating with the lens to define a substantially sealed space around the eyes of a wearer of the goggles the combination comprising, flexible ventilating air inlet forming means projecting through the bottom edge of said frame closely adjacent the inner side of said lens, flexible outlet forming means extending through the top edge of said frame closely adjacent the inner side of said lens and including wall structure forming a plurality of flexibly interconnected passages arranged in side-by-side relation in two or more parallel rows extending longitudinally of the frame, means forming a shield on the outside of said frame extending over said outlet passages and including a plurality of extensions on said outlet forming means bent backwardly over said passages, and means forming a partition between parallel rows of outlet passages including a plurality of extensions depending from one wall of said outlet forming means in close proximity to the inner side of said lens, said extensions in said shield and said extensions in said partition respectively partially overlapping and being free of attachment to each other so that the flexibility of the partition and shield is not appreciably diminished and said

parts are continuous irrespective of the direction in which the frame is flexed.

8. In a ventilated goggles having a lens supported in a frame which has a flexible face contacting part cooperating with the lens to define a substantially sealed space around the eyes of a wearer of the goggles the combination comprising, ventilating air inlet and outlet forming means for establishing communication between said sealed space and the exterior each including means forming a plurality of passageways arranged in side-by-side relation longitudinally of said frame, the said passage forming means including means flexibly to interconnect the adjacent passageways so that flexibility of the frame is not appreciably diminished by the presence therein of the inlet and outlet forming means.

9. In a ventilated goggles having a lens supported in a frame which has a flexible face contacting part cooperating with the lens to define a substantially sealed space around the eyes of a wearer of the goggles the combination comprising, ventilating air inlet and outlet forming means for establishing communication between said sealed space and the exterior including wall structure extending through said frame behind the lens and forming a plurality of passageways arranged in side-by-side relation longitudinally of the frame, at least the portion of said wall structure between the adjacent passageways formed thereby being of at least limited flexibility so that the flexibility of the frame is not appreciably diminished by the presence of the inlet and outlet forming means therein.

10. In a ventilated goggles having a lens supported in a frame which has a flexible face contacting part cooperating with the lens to define a substantially sealed space around the eyes of a wearer of the goggles the combination comprising, ventilating air inlet and outlet forming means for establishing communication between said sealed space and the exterior including wall structure extending through said frame behind the lens and forming a plurality of passageways arranged in side-by-side relation longitudinally of the frame, at least the portion of said wall structure between the adjacent passageways formed thereby being of at least limited flexibility so that the flexibility of the frame is not appreciably diminished by the presence of the inlet and outlet forming means therein, said wall structure being formed of a material of relatively high thermal conductivity.

11. In a ventilated goggles having a lens supported in a frame which has a flexible face contacting part cooperating with the lens to define a substantially sealed space around the eyes of a wearer of the goggles the combination comprising, ventilating air inlet and outlet forming means for establishing communication between the sealed space and the exterior, said inlet and outlet forming means each comprising flexible wall structure extending through said frame and conformed to define a plurality of passageways arranged in side-by-side relation longitudinally of said frame and extensions on portions of the wall structure forming said passageways projecting into the sealed space closely adjacent the inner side of the lens so as to form a continuous baffle for restricting the flow of ventilating air entering said sealed space to the region closely adjacent the inner side of said lens, the wall structure forming said passageways and extensions respectively being flexibly inter-

connected so that flexibility of the frame is not appreciably diminished thereby.

12. In a ventilated goggles having a lens supported in a frame which has a flexible face contacting part cooperating with the lens to define a substantially sealed space around the eyes of a wearer of the goggles the combination comprising, ventilating air inlet and outlet forming means for establishing communication between said sealed space and the exterior each comprising flexible wall structure extending through said frame and conformed to define a plurality of flexibly interconnected passage arranged in side-by-side relation longitudinally of the frame closely adjacent the inner side of said lens so as to tend to restrict flow of ventilating air to the region closely adjacent the inner side of the lens, and extensions on the portions of the wall structure defining the outlet forming means external to the frame bent backwardly over the said outlet forming means, said exten-

sions being conformed partially to overlap when folded back and being free of attachment to each other so that a flexible shield is provided for the outlet forming means which is continuous when the frame is flexed.
